FIBER PREPARATION DEVICE

Carl G. Muench, Glenview, Ill., assignor to The Celotex Corporation, Chicago, Ill., a corporation of Delaware

Application May 3, 1949, Serial No. 91,161

2 Claims. (Cl. 92—7)

1

In the paper and allied arts it has long been customary to digest or cook the fibrous material with various chemicals and with very considerable quantities of cooking liquor in closed boilers of one type or another. Lately there has been developed some apparatus and procedure for the preparation of fibrous material in what might be termed a "dry" process, that is, with but a limited amount of cooking liquor which, in some instances, is present in such a small amount that the fibrous material is merely moistened, and there is little or no free liquor present.

The present invention relates to an apparatus for pretreating or cooking fiber material according to the dry process, that is, wherein normally there is no free liquor, there being utilized only sufficient to moisten the fiber material as distinguished from the use of a large amount of cooking liquor to form a flowable pulp.

In particular the invention relates to a digester wherein the fibrous material, in but moistened condition, is progressed slowly through a pressure vessel, and wherein the fiber is introduced onto a table or shelf-like member and is slowly advanced circumferentially thereon until discharged through an opening in such shelf onto a second shelf, where the procedure repeats followed by the repetition thereof until discharged from the final or lowermost shelf into the bottom of the pressure vessel, whereupon it may be discharged therefrom.

A particular object of the invention is to provide an improved type of apparatus of the character above briefly described, wherein the construction is simple, the device being so constructed that repairs or renewal of the operating parts are greatly simplified, and in particular, wherein the fiber material, during its processing within the device, is relatively undisturbed. That is, the fibrous material is cooked or digested without kneading or rubbing, or the like, of the material in its relatively raw and unprepared state. Specifically, the objects of the invention constitute the accomplishment of the matters just aforesaid, and include other improvements and advances which will be apparent to those skilled in the art upon reading this specification, taken together with the accompanying drawings.

In the accompanying drawings the device is disclosed in Figure 1 as substantially a cross-section of the device taken on line 1—1 of Figure 2;

Figure 2, a horizontal cross-section taken on line 2—2 of Figure 1, and

Figure 3, a cross-section taken on line 3—3 of Figure 1.

The device constitutes a pressure shell or boil-

er, the body of which is designated by numeral 10, the top head by 11, and the bottom head by 12. It is understood, of course, that the top and bottom heads 11 and 12, respectively, are suitably bolted together at their flanges 13 by means of bolts 14. Mounted within the pressure shell body 10 there is provided a cage, the vertical arms of which are designated by the numeral 15, which vertical arms connected by top and bottom spider portions 16 and 17, respectively. The top spider 16 is separate from the vertical arms 15, as is clearly apparent in the drawing, and may be secured thereto by suitable countersunk screws or the like, which actual fastening means are not illustrated, but the provision of which will be readily apparent to any mechanic.

The top spider arms 16 are connected to a collar member 18 which is central with respect thereto, and from which the spider arms 16 project radially. It will be understood, of course, that the spider arms and vertical arm members 15 are not limited to three only, but there may be provided two such or four or five or any other practical number, as these portions constitute merely a skeleton or frame to which the other portions of the internal structure of the device are connected or on which they are mounted. Centrally, the lower spider arms 17 merge into a central collar or bearing 18.

The shell portion 10 of the device is provided around its periphery, internally, with suitable recesses 25 to receive the vertical arms 15 of the cage, and it will be understood, of course, that the number of these recesses 25 provided correspond to the number of vertical arms of which the cage portion is composed. The side walls of these recesses 25 comprise abutments which restrain rotation of the cage member due to the restraining effect with respect to the vertical arms 15 of the cage member.

Suitably mounted in the cage member and secured to the vertical arms 15 there are shelf or table members 26 which are circular members, each having a cut-out, as will be hereinafter described. These shelf members 26 are suitably secured to the vertical arms 15 as by welding, or it is readily understood they may be secured thereto in any desired manner. These shelf members 26 are spaced apart vertically a distance which, of course, will be largely a matter of design, that is, they will be spaced sufficiently to accommodate the amount of fiber material which is to be handled and will be provided in sufficient number to provide, in conjunction

55 with the other designed elements, for the de-

sired time interval of progression of the fiber material through the device. Merely as an example, it may be taken that the device is provided with five of the table members 26 spaced vertically, one from another, 12 inches. As will be readily understood from the entire description, the number of the table members and spacing, as referred to, is merely arbitrarily taken, and in actual practice it will be more likely that there will be something like 20 of the table members 26 with approximately six inch spacing.

In the head portion 11 of the shell there is provided a bearing and seal 27 in which may be mounted shaft 28, on which shaft 28, immediately above each of the shelves 26, there is mounted a member 29 having radial arms 30, and which is pinned to shaft 28 by a pin 31 or the equivalent.

Also provided in the head portion 11 of the shell there is a fiber supply device 35 for supplying moist fiber and discharging it upon the topmost table 26 within the shell. This fiber supply device may be a pressure screw 36 operating within the supply conduit 35, or may be any other suitable device for feeding the fiber into the device against steam pressure maintained therein.

For rotating shaft 28 there may be provided a gear 40, and for the introduction of suitable chemicals, water if desired, and steam, there may be provided chemical supply piping 41, steam supply piping 42 and water supply piping 43, each suitably secured in the shell head 11. At the bottom of the device, and forming a part of or secured in the shell body 12, there is provided a discharge conduit 44 in which there may be a valve 45, and also suitably mounted to said shell bottom 12 there are provided water jet nozzles 46 supplied by piping 47.

Discharge valve 45 is a vane or measuring valve which discharges the pulp stock from the digester at substantially atmospheric pressure while retaining full pressure in the digester. Valve 45 comprises a cylindrical body in which mounted on shaft 51 there are provided radial vanes 52 between which are formed pulp receiving pockets. The valve may be operated at the required speed by gear 53 mounted on shaft 51. In operation the spaces between the vanes fill with the pulp stock from the digester and as the valve rotates, these charges are successively discharged, as is readily apparent in the drawing. The specific valve construction is shown only as an example, and any equivalent throttling or pressure retaining discharge device may be employed.

According to the specific disclosure hereof, and since each of the sets of radial rotating arms 30, operating in cooperation with and with respect to shelf members 26, is provided with six equally spaced radial arms which are thus 60 degrees apart, it results that the openings or cut-out portions of the shelf members 26 are approximately a 60 degree segment of a circle, and that the successive openings in the respective shelves 26, considered downwardly, are positioned, displaced, 60 degrees with respect to their respective edges in a direction counterclockwise with respect to the opening through the shelf member 26 immediately above. It will thus be seen that fiber material discharged into one of the radial segments will be carried around between a pair of radial arms 30 until it comes to an opening through shelf 26, whereupon the fiber material will discharge through the opening under the influence of gravity and will fall upon shelf 26 immediately below, and will be received thereon between a pair of radial arms 30 cooperating therewith. This, of course, assumes that shaft 75 has been subjected.

28 and radial arms 30 mounted thereon are rotated in clockwise direction, and it will be understood, of course, that should the rotation be in reverse direction, that the respective openings through the shelf members 26, going downwardly through the device, will be displaced in a clockwise direction.

As the fiber material from the topmost shelf is discharged onto the next lower shelf member 26, it will be received between a pair of cooperating radial arms 30 and carried around and discharged through the opening in the second shelf, and thence serially likewise the fibrous material will be discharged through an opening through each next succeeding shelf member 26, and carried around on the shelf between a pair of cooperating radial arms 30 until finally this fibrous material is discharged from the opening through the lowermost shelf member 26 to the bottom portion of the shell. The fiber, when discharged from the lowermost shelf member 26 into the shell bottom 12, may be diluted to a flowable consistency by water introduced under pressure through jet nozzles 46, and this flowable pulp may then flow out of the device through the discharge conduit member 44.

Any suitable digesting chemical may be supplied to the fiber as it enters the device, or may be supplied to the fiber material as it is received on the top most shelf member 26, such being introduced under pressure through piping 41. The type of digesting chemical or amount thereof will, of course, depend on the type of raw fiber material supplied and the type of and extent of digestion to be carried out within the device. The chemical supplied may be an ordinary caustic cooking liquor, or may be in the nature of a kraft liquor, or a sulphite or modified sulphite liquor or the like, it being understood, of course, that such is supplied in a relatively concentrated form so that, as previously referred to, the fiber material is only moistened or wetted and is not in any sense of the word a pulp as such is ordinarily considered, but it is merely a mass of dampened fiber. Steam pressure, as desired to accomplish the amount of cooking or digesting required with the specific chemical added, is maintained by means of steam introduced through piping 42 and, if desired, additional water may be introduced through piping 43, or water may be introduced through this piping for washing out the device when such is desired.

It will be seen that fiber material may be digested in the device hereof according to any predetermined procedure, and that dependent upon the speed of rotation of the shaft 28 and number of shelves 26 and cooperating radial arms 30, the fiber may be subjected to any period of digestion desired. In this device the fiber material is not rubbed, kneaded or otherwise worked during the period of its digestion. It is merely carried slowly through the device in a substantially quiescent condition except for the gentle tumbling, mixing action which occurs as the masses are discharged from one level to the next lower level, merely falling by gravity, and thus the non-fibrous lignins and the like may be chemically acted upon without subjecting the fibrous substance, while relatively brittle, to deleterious mechanical action, so that the resulting digested fiber material comprises uninjured fibers with the lignins and the like disintegrated or digested to such extent as is desired, depending upon the specific digestion process to which the material has been subjected.

A particular advantageous feature of the construction disclosed is that for repairs or overhauling the entire interior operating portion of the device is readily removable, as it is only necessary to remove the bolts or the like securing head 11 to the shell 10, and then the entire interior assembly may be withdrawn from the shell. After withdrawal of the interior assembly from the shell, upon removal of the securing pins or the like, 31, securing radial arm members to the shaft, then shaft 28 may be withdrawn and the various radial arm members may be removed and the entire interior construction is readily accessible for cleaning or renewal or the like.

The construction of the device hereof and the operation thereof having been above fully disclosed, what I claim is:

1. A digester construction comprising a housing shell, top and bottom heads therefor, one of such heads removably mounted to and secured to the shell, a removable assembly mounted in the housing shell, the removable assembly comprising an elongated unitary cage member, central shaft bearings mounted to the unitary cage member centrally thereof at each end, spaced shelf members mounted to the cage member, a central shaft carried by the cage member and mounted in said shaft bearings, groups of spaced substantially radial arms mounted in spaced relation along and to the shaft and positioned thereon to sweep over the upper surface of each of the shelf members, each shelf member having a segmental opening therethrough and of configuration and dimensions substantially that of the area encompassed between adjacent substantially radial arms of a group thereof, the openings in the shelf members circumferentially offset with respect to such openings in adjacent shelves by an amount substantially equal to the width of a such opening, the shell interiorly thereof providing abutment surfaces and the such abutment surfaces and portions of the unitary cage member engaging and restraining relative rotation of the cage member with respect to the shell.

2. A digester construction comprising a housing shell, top and bottom heads therefor, one of such heads removably mounted to and secured to
